UNITED STATES PATENT OFFICE.

GEOERGE E. THOMPSON, OF OWATONNA, MINNESOTA.

DESIGN FOR A BALL FOR LIGHTNING-RODS AND BARN-VENTILATORS.

56,715.

Specification for Design.

Patented Nov. 30, 1920.

Application filed May 26, 1919. Serial No. 299,993. Term of patent 14 years.

To all whom it may concern:

Be it known that I, GEORGE E. THOMPSON, a citizen of the United States, residing at Owatonna, county of Steele, State of Minnesota, have invented a new, original, and ornamental Design for a Ball for Lightning-Rods and Barn-Ventilators, of which the following is a specification, reference being had to the accompanying drawing, forming part thereof.

The figure is a side elevation showing my new, ornamental ball design.

I claim:

An ornamental design for a ball for lightning rods and barn ventilators, as shown.

In witness whereof I have hereunto set my hand this 13th day of May, 1919.

GEORGE E. THOMPSON.

Witnesses:

S. M. HAWKINS,
GLADYS A. NIELLS.
